INDICIA COVER FOR GAME BOARD

Mark Herring, Scottsbluff, Nebr., assignor to James A. Warner and Margie Louise Warner, both of Scottsbluff, Nebr.

Original design application June 19, 1969, Ser. No. 17,776. Divided and this application Feb. 20, 1970, Ser. No. 21,533

Term of patent 14 years

Int. Cl. D21—01

U.S. Cl. D34—5

FIG. 1

FIG. 2

FIG. 4

FIG. 3

FIG. 5

FIG. 6

FIG. 1 is a top plane view of an indicia cover for game board showing my new design.

FIG. 2 is a bottom plan view thereof.

FIG. 3 is an elevation view taken from one side thereof, the opposite side being a mirror image of the side shown.

FIG. 4 is an elevation view of one end thereof.

FIG. 5 is an elevation view of the other end thereof.

FIG. 6 is a cross-section view taken on line 6—6 of FIG. 3.

This is a division of pending application D. 17,776, filed June 19, 1969.

I claim:

The ornamental design for an indicia cover for game board, as shown and described.
